UNITED STATES PATENT OFFICE.

PETER J. MACDONALD, OF NOANK, CONNECTICUT.

BLOCK.

SPECIFICATION forming part of Letters Patent No. 691,558, dated January 21, 1902.

Application filed February 14, 1901. Serial No. 47,240. (No model.)

To all whom it may concern:

Be it known that I, PETER J. MACDONALD, a citizen of the United States, and a resident of Noank, in the county of New London and 5 State of Connecticut, have invented a new and Improved Block, of which the following is a full, clear, and exact description.

This specification is a specific description of one form of the invention, while the claims 10 are definitions of the actual scope thereof.

Reference is to be had to the accompanying drawings, forming a part of this specification, in which similar characters of reference indicate corresponding parts in both the views.

15 Figure 1 is a sectional view of the block, and Fig. 2 is a side view of the same.

It is immaterial with what number of sheaves the block is fitted, since the principle of construction of the block will be the same. The shell of the double block is made up of two pairs of metallic plates *h*, between the members of each of which are the sheaves *i*. These plates *h* have their end portions turned laterally to form flanges *h'*, and between these flanges cheek-pieces *k* are arranged. Situated between the members of the pairs of plates *h* are spacers *l*, which are essentially segmental in form, and these parts *h* and *l* are held rigidly together by rivets *m*, 30 passed transversely through the block and occupying the positions best shown in Fig. 2. The sheaves *i* are mounted on a pin *n*, which is the same as the pin usually employed. If desired, the sheaves *i* may be "patent" or 35 "common" sheaves, as desired.

Arranged between and at each side of the sheaves *i* are the straps *o* of the block, which straps slide freely in openings formed in the flanges *h'* of the plates *h*. These straps are 40 therefore three in number, and they are joined together at their lower ends to form a becket *o'* to permit the attachment of the block to the traveler or to any other part to which the block is to be secured. The straps *o* are 45 formed with longitudinal slots *o*², which receive the pin *n* and which permit the relative movement of the straps and the shell of the block, the shell carrying with it the pin *n* and the sheaves *i*. The upper segmental spacers *l* 50 are provided with rods *p*, which are rigidly attached thereto or formed integral therewith,

as desired, and which project loosely through openings in a cross-plate *q*, rigidly attached to extensions *o*³ of the straps *o*. The rods *p* carry expansive spiral springs *r*, and these 55 springs bear between the adjacent blocks *l* and the cross-plate *q*. The rods *p* project beyond the cross-plate *q* and are connected with a shackle *s*, which spans between the rods and is joined thereto by a pin *s'*. 60

The springs *r* may be of any material desired. In a block thus constructed the shell carrying with it the pin *n* and the sheaves *i* will be free to move on the straps *o*, according to the strength of the springs *r*, and when 65 the strain on the block becomes greater than the strength of the springs the springs will give, thus permitting the sheaves and the shell of the block to move relatively to the straps. In actual construction this relative 70 movement may be permitted in a radius of three to six inches, according to the size of the block.

Having thus described my invention, I claim as new and desire to secure by Letters 75 Patent—

1. A block, comprising a shell, a sheave mounted therein, straps formed with slots loosely receiving the pin of the sheave, the straps being slidably fitted in the shell, and 80 a spring bearing between the straps and the shell, for the purpose specified.

2. A block, having a shell, a sheave mounted therein, straps having sliding connection with the sheave, a cross-plate extending between the straps, a rod in connection with the shell of the block, the rod sliding in the cross-plate, and a spring bearing between the cross-plate and the shell of the block. 85

3. A block, having a shell, a sheave mounted therein, straps movable relatively to the shell and sheave and projecting past each end of the shell, and a spring acting between the straps and the shell, for the purpose specified. 90

In testimony whereof I have signed my 95 name to this specification in the presence of two subscribing witnesses.

PETER J. MACDONALD.
